MAILBOX LETTER HOLDING ASSEMBLY

Filed Sept. 22, 1950

UNITED STATES PATENT OFFICE

2,634,050

MAILBOX LETTER HOLDING ASSEMBLY

Otto H. Hibbeler, Omaha, Nebr.

Application September 22, 1950, Serial No. 186,229

1 Claim. (Cl. 232—33)

1

This invention relates to rural mail boxes of the type having a front door, and in particular an attachment for a mail box which provides means on the inside of the door for holding letters and the like whereby the letters are accessible so that they may readily be picked up by a mail man.

The purpose of this invention is to provide an improved mail box from which letters may readily be taken by the postman without the necessity of running an arm into the box and which also eliminates the inconvenience of picking up a flat article, such as a thin letter or postcard from a flat surface.

In the conventional type of rural mail box letters, postcards and the like are placed on the inner surface of the bottom of the box and these are not only difficult to pick up, but in numerous cases where the light is weak it is difficult to determine whether or not there is mail in the box. With this thought in mind this invention contemplates providing means on the inside of the door of a mail box for retaining mail in suspension so that it is only necessary for the carrier to open the door, take the mail, and close the door.

The object of this invention is, therefore, to provide means for forming letter supporting elements on the inside of a door of a mail box whereby letters and the like may readily be inserted therein and also readily removed therefrom.

Another object of the invention is to provide letter retaining elements that may readily be installed on the inside of a door of a mail box.

Another object of the invention is to provide a letter supporting device to be attached to the inside of a mail box door in which letters, cards and the like are retained therein by friction.

A further object of the invention is to provide a device for retaining letters and the like in suspension on the inner surface of the door of a mail box which is of a simple and economical construction.

With these and other objects and advantages in view the invention embodies a pair of brackets carried by a base plate positioned on the inside of a mail box door, opposed sponge rubber blocks carried by the brackets, means pivotally mounting one of the brackets and resilient means urging the sponge rubber block of the pivotally mounted bracket toward the block of the other bracket.

Other features and advantages of the invention will appear from the following description taken in connection with the drawings, wherein:

2

Figure 1 is a front elevational view looking toward the open end of a mail box with the door opened to a horizontal position and showing the letter holding elements with a letter indicated therein in dotted lines.

Figure 2 is a side elevational view showing the front end of a mail box also with the door open and with parts broken away, and showing a portion of a letter in the holding elements in dotted lines, with part of the letter broken away.

Figure 3 is a detail on an enlarged scale showing an elevational view of the pivotally mounted letter holding bracket.

Referring now to the drawings wherein like reference characters denote corresponding parts the mail box letter holder of this invention includes a base plate 10, a stationary bracket 12 with a sponge rubber block 14 therein, a pivotally mounted or swinging bracket 16 with a sponge rubber block 18 therein, a spring 20, and studs 22 and 24 for pivotally mounting the bracket 16 in the upper ends of uprights 26 and 28.

The base plate 10 is secured to the inner surface of a door 30 of a mail box 32 by welding or other suitable means, and a Z-bar 34 having a web with a flange 36 on the upper end and a flange 38 on the lower end is mounted on the base plate by welding or otherwise securing the flange 38 to the plate. A flange 40 on the lower end of the web of the bracket 12, which is also in the form of a Z-bar, is mounted on the flange 38 and a flange 42 on the upper end of the bracket extends over the flange 36 on the upper end of the bar 34, as shown in Figure 1.

The inner surfaces of the flanges 36 and 42 are provided with teeth 44 and 46, respectively, which secure the sponge rubber block 14 in the stationary bracket with the edge of the block extended beyond the ends of the flanges. The bar 34 is secured to the bracket 12 by welding, soldering, or other suitable means.

The bracket 16 which is pivotally mounted in the upper ends of the posts or uprights 26 and 28 by the studs 22 and 24, is formed with webs, one of which is provided with a flange 48 at the upper end and a coacting flange 50 is provided on the other web, which is indicated by the numeral 52, and the web 52 is secured to the inner face of the bracket. The coacting surfaces of the flanges 48 and 50 are provided with teeth, similar to the teeth 44 and 46, of the flanges 36 and 42, and the teeth of the flanges 48 and 50 hold the block 18 in the bracket.

The spring 20 is secured, at one end, to the base plate 10, and the opposite end is held on a tang 54 on the rear surface of the pivotally mounted bracket 16, as shown in Figure 3.

With the parts arranged in this manner, the door of the mail box is opened, as shown in Figures 1 and 2, and by drawing the block 18 away from the block 14, a letter or the like, as indicated by the numeral 56, is placed between the blocks, and as the block 18 is released, the letter is firmly gripped between the blocks until it is withdrawn manually by a carrier.

The blocks 14 and 18 are described as formed of sponge rubber, and it will be understood that the blocks and also other parts of the device may be formed of any material desired. It will also be understood that the blocks may be of any suitable shape or design, and other means may be used for suspending the blocks from the inner surface of the mail box door.

From the foregoing description it is thought to be obvious that a mail box letter holding assembly constructed in accordance with my invention is particularly well adapted for use by reason of the convenience and facility with which it may be assembled and operated, and it will also be obvious that my invention is susceptible of some change and modification without departing from the principles and spirit thereof, and for this reason I do not wish to be understood as limiting myself to the precise arrangement and formation of the several parts herein shown in carrying out my invention in practice, except as claimed.

Having thus fully described the invention what I claim as new and desire to secure by Letters Patent is:

In a mail gripping bracket for use in a mail box, the combination which comprises a base plate, a Z-bar mounted on the base plate, said Z-bar having a web positioned perpendicular to the base plate, a mounting flange secured to the base plate and a flange parallel to the base plate and extended at a right angle from the extended end of the web, a bracket, Z-shape in cross section, having a web positioned against

the web of the Z-bar with a mounting flange secured to the mounting flange of the Z-bar and a flange parallel to the base plate and extended from the end thereof extended from the base plate, said flange on the extended end of the bracket being spaced from the flange on the extended end of the web of the Z-bar, a block of resilient material positioned between the flanges of the Z-bar and bracket and extended beyond the extended edges of said flanges, spaced posts extended from said base plate positioned in spaced relation to the Z-bar and bracket, a swinging bracket having webs with spaced flanges extended from extended ends thereof positioned between said posts, means pivotally mounting said swinging bracket by means of the webs thereof in said posts, a block of resilient material positioned between the flanges of the swinging bracket, the flanges of the brackets between which the blocks of resilient material are positioned having teeth on opposed faces thereof for gripping the blocks of resilient material, and a spring attached to the base plate at one end and at the opposite end to an end of the swinging bracket extended from the pivotal mounting of the bracket toward the base plate, said spring and posts positioned whereby the extended face of the block of resilient material of the swinging bracket is urged into meeting relation with the extended face of the block of resilient material of the Z-bar and bracket secured to the base.

OTTO H. HIBBELEER.
